UNITED STATES PATENT OFFICE.

NILS O. STARKS, OF MADISON, WISCONSIN, ASSIGNOR TO THE FULLER & JOHNSON MANUFACTURING COMPANY.

CORN-PLANTER.

SPECIFICATION forming part of Letters Patent No. 354,025, dated December 7, 1886.

Application filed September 15, 1886. Serial No. 213,610. (No model.)

To all whom it may concern:

Be it known that I, NILS O. STARKS, of Madison, in the county of Dane and State of Wisconsin, have invented certain new and useful Improvements in Corn-Planters; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved seed-box and tube for corn-planters, showing portions broken away. Fig. 2 is a top view of the seed-slide and disk, showing the seed-box and its bottom removed. Fig. 3 is a vertical sectional view on line *x x*, Fig. 2, through the entire box and tube. Fig. 4 is a similar view on line *y y*, Fig. 2. Fig. 5 is a perspective view of the seed-slide and of its pawls, one pawl being shown removed. Fig. 6 is a similar view of the dropping mechanism in the seed-tube, showing portions broken away and indicated in dotted lines; and Fig. 7 is a partially-sectioned view of the reverse side of said dropping mechanism.

Similar numerals of reference indicate corresponding parts in all the figures. My invention has relation to that class of seedling-machines in which a horizontal seed-disk is journaled in the bottom of the seed-box and engaged by pawls upon a reciprocating slide, and in which a valve at the lower portion of the seed-tube is alternately tilted to one side or the other by a suitable lever-connection with the slide; and it consists in the improved construction and combination of parts of such a seedling-machine, as herein-after more fully described and claimed.

In the accompanying drawings, the numeral 1 indicates the seed-box, which is secured to the transverse frame-piece 2, having the downwardly-projecting bar 3, to which the shoe is secured. A frame or casting, 4, is secured upon the frame-piece under the seed-box, and is formed with a longitudinal slot, 5, near the side edges, and with upwardly-turned flanges 6 at the edges, the said flanges having apertures 7 at the ends of the frame for the passage of the sliding frame.

The center of the frame is provided with a circular raised bed, 8, having a central perforation, 9, and a stud, 10, fits into this perforation, projecting downward from the center 55 of the seed-disk 11, which revolves with this central bolt upon the circular bed, and is formed with a number of perforations or seed-cups, 12, which register with a perforation, 13, in the bed near the edge of the same. 60

The bottom 14 of the seed-box is retained within the same by means of slotted cleats 15, sliding upon screws 16 in the end pieces of the box, and bearing with their ends against the bottom, and this bottom has a central 65 aperture, 17, of a sufficient diameter to expose all the seed-cups in the revolving seed-disk. A tongue, 18, projects obliquely into this central aperture from the edge of the same, and a bent flat plate, constituting a scraper or cut-off, 19, is pivoted with laterally-projecting lugs at its bend between the inner side of the tongue and the edge of the aperture, covering some of the seed-cups in the disk above the discharge-aperture and bearing with its end 70 against the upper side of the disk. The other end of the cut-off or scraper bears against a coiled spring, 20, inclosed in a casing, 21, upon the bottom, the spring allowing the scraper or plate to yield to portions of a grain 75 of corn, which might project above a seed-cup as it passes under the scraper, the scraper serving to prevent the cups from being more than filled.

The periphery of the seed-disk is provided 85 with a number of ratchet-teeth, 22, beveled upon their upper sides toward the oblique edges of the teeth, and these ratchet-teeth are engaged by pawls 23, pivoted to point in opposite directions upon the inner sides of the 90 side pieces of the open rectangular frame 24 of the sliding frame.

The frame of the slide is provided with two projecting frames, 26, at its ends, having each a longitudinal rail, 27, at the middle, registering with longitudinal rails 28 upon the upper face of the supporting-casting and anti-friction rollers support the slide, being composed of two disks, 30, connected by a reduced central portion, 31, the rollers straddling the 100 rails with the reduced portions and traveling against the upper face of the supporting-frame

and the lower face of the slide-frame at both sides of the rails with the disks. One end of the sliding frame is provided with a lip, 32, to which the reciprocating mechanism is connected.

The inner sides of the side pieces of the rectangular sliding frame are formed each with an inwardly-projecting lug, 33, at opposite ends of the said side pieces, and lips 34 and 35 project from the end pieces of the frame at a short distance from the side pieces, forming notches 36 and 37, and the pawls are formed with perforations 38 at their inner ends, with which perforations they fit upon the studs upon the side pieces, and have their inner ends so shaped that they will catch into the notches in the end pieces of the frame when tilted downward in their normal position, while they will have to be raised in an upright position to be allowed to slip off the studs, the distance between the perforations and the upper edges of the pawls being less than the distance between the perforations and the inner ends.

The lower edges of the pawls are formed with the shoulders 39, which engage the ratchet-teeth of the seed-disk, and may slip over their beveled faces with their beveled or inclined edges 40, and at the outer ends the pawls are furthermore provided with downwardly-projecting lugs 41, having tongues 42, engaging the notches at those ends in the end pieces, the said lugs serving to engage the ratchet-teeth and to carry the disk back if the shoulders of the pawls should fail to engage the ratchet-teeth and to carry the disk sufficiently around, so that the shoulders may engage the teeth at the next stroke of the slide. The free ends of the pawls are provided with laterally-projecting lips 77, which rest upon the upper edges of the side pieces of the frames, preventing the pawls from dropping down too far.

The inner side of one of the side pieces of the slide-frame is provided with two inwardly-projecting lugs, 43, between which the outwardly and upwardly bent upper end, 44, of a lever, 45, projects, so that the lever may be tilted by each stroke of the slide. The middle of this lever is flattened and formed with a perforation, 46, and with a downwardly-facing segmental shoulder, 47, above the perforation and concentric with the same, and with a segmental slot, 48, concentric with the perforation and below the same, and the lever is pivoted with the perforation upon a lug, 49, projecting from the inner face of a casting, 50, secured to the supporting-bar of the shoe or runner by a screw, 51, passing through a perforation, 52, in the casting and through the segmental slot of the lever. The upper end, 53, of the casting is segmental, having the correspondingly-shaped shoulder of the lever fitting against it, and the side edges of the casting are formed with flanges 54, bearing against the face of the supporting-bar and forming a casing for the lever. A three-sided box, 55, fits with lips 56 against the sides of the bar,

forming a tube with the face of the bar, inclosing the lever and leading from the seed-aperture of the seed-box, and the lower end of this box incloses two upwardly-diverging flanges or-walls, 57, upon the edges of the outer face of the casting, near the lower end of the same, and the lower ends of these flanges are formed with diverging portions 58, forming parts of a cylinder. The lower end of the casting is formed with an outwardly-projecting stud, 59, having a notch, 60, in its end, and with an inwardly-extending circular casing or box, 61, having a slot, 62, in its upper side, through which the lower end of the lever projects, the said lower end being provided with cogs 63.

The lower end of the three-sided box is formed with an aperture, 64, in its outer side, extending from the lower end of the said side, and a lid or cover, 65, is secured over the said aperture and over the lower portion of the casing formed by the cylindrical diverging walls and by the stud, bearing with an inwardly-projecting lip, 66, at its lower pointed end into the notch in the end of the stud.

The cover is formed with an aperture, 67, in its upper portion, having its edges recessed upon the inner side, and a glass plate, 68, fits into these recessed edges, covering the aperture. A screw-bolt, 69, passes through a perforation in the cover and through an aperture, 70, in the center of the bottom of the circular casing of the casting, into the supporting-bar, securing the cover and the casting to the said bar, and a valve, 71, is pivoted with a central perforation, 72, upon the smooth portion of this bolt. This valve consists of a portion, 73, forming a cylinder-sector, which portion may fit with its cylindrical outer side against either of the cylindrical walls or flanges at the lower end of the seed-tube, and the lower portion of the valve is formed by two diverging curved wings, 74, which form seed-cups between them and the sides of the sector-shaped portion. The inner side of the valve is provided with a cogged segment, 75, projecting into the circular casing and meshing with the cogged lower end of the lever.

It will now be seen that as the sliding frame is reciprocated the seed-disk will be revolved for each stroke of the slide, one pawl engaging a ratchet-tooth at one side at one stroke and the pawl upon the opposite side engaging a tooth upon that side at the back-stroke, and the disk will be moved forward at each stroke the space of one seed-cup, the number of seed-cups in the disk being twice the number of the ratchet-teeth. The sliding frame will rock the lever which operates the valve in the lower end of the seed-tube, and this valve will be rocked at each stroke, so as to bring one cup facing up in the tube and receiving the corn dropped from the seed-cup in the disk, while the other cup of the valve will be tilted down, dropping the corn.

The under side of the sliding frame is formed with suitable stops or concave shoulders, 76,

at its ends, for the purpose of stopping the rollers at the end of each stroke as they travel between the slide and the frame.

It will be seen that the pawls may be removed from their studs by simply raising them and thereupon sliding them off the studs, and that they may be placed upon the studs in the same manner, so that it will require no tools or complicated fitting to remove or insert a pawl in case one or both of the pawls should break or become worn, the pawls being inserted in the same shape in which they are removed from their molds.

The rollers will cause the sliding frame to reciprocate easily, and will prevent its being obstructed by dust from the corn, as the rollers will travel over obstructions and push them aside, over which a sliding surface could not travel without considerable frictional resistance. The pivotal stud for the seed disk, projecting into a perforation in the bottom plate or frame, will prevent the said perforation and stud from becoming clogged by dust, as is liable to happen if the disk is journaled with a central perforation upon a stud projecting from the bottom plate, as seed-disks generally are pivoted.

All the moving and meeting faces of the movable portions of the lever and valve in the seed-tube are covered in such a manner that dirt from the seed cannot obstruct the said surfaces, the segmental shoulder of the lever bearing against the segmental upper edge of the casting in the lower end of the seed-tube, and the cogged end of the lever and the cogs of the valve being inclosed in the circular casing.

The downwardly-projecting lugs upon the outer ends of the pawls or latches of the sliding frame will serve to draw the seed disk back by engaging the ratchet-teeth on the back-stroke if the forward stroke has failed to carry the disk the desired distance forward, enabling the pawl to carry the disk around at the next stroke.

Having thus described my invention, I claim and desire to secure by Letters Patent of the United States—

1. The combination, with the sliding frame, whose side pieces are provided with notches 36 and 37 and lugs 33, of the pawls formed with lips 77 and perforations 38, the distance between the perforations and the upper edges of said pawls being less than the distance between said perforations and the inner ends of the pawls, as and for the purpose set forth.

2. The combination, with the rotary seed-disk provided with ratchet-teeth 22 and the sliding frame, of the pawls 23, pivoted to the side pieces of said frame and provided with

shoulders 39, and the tongue-bearing lugs 41, to operate substantially as set forth.

3. In a seeding-machine, the combination of a casting at the lower end of the seed-tube, formed with diverging cylindrical walls or flanges facing downward, and having a circular casing below the flanges in its inner side concentric with the flanges and open in its upper side, a lever pivoted to the casting and having its upper end engaged and reciprocated by the sliding frame, and having its lower end provided with cogs, and a valve pivoted upon a bolt in the center of the circular casing and having a cogged segment projecting into that casing and engaging the cogs of the lever, and having a portion shaped as a cylinder-sector alternately bearing against the cylindrical walls, and curved wings forming seed-cups between them and the sector-shaped portion, as and for the purpose shown and set forth. 80

4. In a seeding-machine, the combination of the shoe supporting bar, a three sided casing covering the rear side of the said bar and forming a tube with it, having the lower end of its outer side cut away, a casting secured upon the rear side of the bar within the casing and having its upper edge segmental, and having a central stud upon its rear side and flanges at the edges of its rear side, and a perforation below the stud, and formed with upwardly-diverging walls at the edges of its outer face, continued into diverging cylindrical flanges at their lower ends, and with a circular casing at its lower end, formed with its upper side open, and an outwardly-projecting stud below the casing, a lever engaged and reciprocated at its upper end by the seed-slide and pivoted upon the stud of the casting, having a segmental shoulder bearing against the segmental upper edge of the casting and a segmental slot below the stud and having a cogged lower end, a cover having a plate of glass inserted in its upper portion and fitted over the cut away portion of the seed-tube, having a bolt passing through it into the shoe supporting bar and a tongue upon its lower end engaging a notch in the stud at the lower end of the casting, and a cylindrical valve having seed-cups in its periphery and a segmental rack upon its inner side engaging the cogs of the lever within the circular casing, being journaled upon the bolt securing the cover, as and for the purpose shown and set forth. 100

In testimony that I claim the foregoing as my own I have hereunto affixed my signature in presence of two witnesses.

NILS O. STARKS.
